(57) **CLAIM**

The ornamental design for a window sash latch, as shown and described.

DESCRIPTION

FIG. 1 is a top front perspective view of a window sash latch showing my new design.

FIG. 2 is a bottom front perspective view of the window sash latch of FIG. 1.

FIG. 3 is a top rear perspective view of the window sash latch of FIG. 1.

FIG. 4 is a front elevation view of the window sash latch of FIG. 1.

FIG. 5 is a rear elevation view of the window sash latch of FIG. 1.

FIG. 6 is a right elevation view of the window sash latch of FIG. 1.

FIG. 7 is a left elevation view of the window sash latch of FIG. 1.

FIG. 8 is a top plan view of the window sash latch of FIG. 1; and,

FIG. 9 is a bottom plan view of the window sash latch of FIG. 1.

The broken lines depict portions of the window sash latch that form no part of the claimed design.
